UNITED STATES PATENT OFFICE

2,609,843

COMPENSATING SPRING TAKE-UP TENSION
FOR BOBBIN CHANGE SHUTTLES

Charles H. Durham, Bedford, Va.

Application June 15, 1951, Serial No. 231,736

5 Claims. (Cl. 139—215)

1

This invention relates to a novel spring take-up tension capable of being readily applied to a standard tension of the type commonly used in bobbin change shuttles and which will effectively take up any slack in the yarn or filling when the shuttle strikes the picker, to thereby eliminate serious defects now resulting in woven cloth where no means is provided by the conventional tension for taking up slack and maintaining uniform tension on the filling.

Another object of the invention is to provide a compensating spring take-up tension for use as an attachment for a conventional tension which will maintain an even tension at all times on the filling and which may be employed with any type of yarn and with modern high-speed loom shuttles.

Various other objects and advantages of the invention will hereinafter become more fully apparent from the following description of the drawing, illustrating a presently preferred embodiment thereof, and wherein:

Figure 1 is a fragmentary plan view of the forward end of a shuttle showing the invention applied to a conventional tension;

Figure 2 is a side elevational view thereof looking from bottom to top of Figure 1;

Figure 3 is a top plan view of a conventional tension equipped with the invention and shown removed from the shuttle;

Figure 4 is a side elevational view looking from bottom to top of Figure 3;

Figures 5 and 6 are horizontal sectional views taken substantially along planes as indicated by the lines 5—5 and 6—6, respectively, of Figure 4;

Figure 7 is an end elevational view looking from right to left of Figure 4;

Figure 8 is a side elevational view looking from right to left of Figure 7;

Figure 9 is a cross sectional view taken substantially along a plane as indicated by the line 3—9 or Figure 4, and

Figure 10 is an enlarged exploded perspective view illustrating certain of the parts of the invention.

Referring more specifically to the drawing, the forward portion of a shuttle body, designated generally 10, of conventional construction is shown in Figures 1 and 2. The shuttle 10 has the usual cavity 11 in which is disposed a conventional bobbin 12 carrying the filling or yarn 13. The forward end or nose 14 of the shuttle 10 is provided with the usual depression 15 which opens into the forward end of the cavity 11, is open at its top and opens outwardly of one side of the nose 14, as seen at 15. The de-

2

pression 15 is of the proper shape and size to accommodate a conventional tension 17 which is detachably secured therein by a fastening 18. The tension 17 has a channel 19 through which the yarn extends forwardly and said tension is provided with the usual opposed spring urged pads 20 which extend into the channel 19 and between which the yarn 13 passes. The pads 20 grip the yarn to resist movement thereof away from the bobbin 12 but afford no means for taking up any slack in the portion of the yarn which extends outwardly through the cavity opening 15. The parts previously described are all of conventional construction.

15 The compensating spring take-up tension, designated generally 21 and comprising the invention, constitutes a unit which is detachably mounted in the tension 17 and which functions therewith. For this purpose the body of the tension 17 is provided with a slot 22 which is disposed substantially parallel to its bottom surface to loosely accommodate a lever 23 which is mounted for swinging movement in the slot 22 by a pin 24 which extends loosely through the inner end of said lever 23 and perpendicularly through the slot 22. The body of the tension 17 is also provided with a bore 25 which is disposed in the same plane as the slot 22 and has one end opening into said slot and its opposite end opening outwardly of a side wall 26 of the tension body. As best seen in Figure 4, a plate 27 is secured against the wall 26 by a screw fastening 28 and overlies the end of the bore 25 which opens outwardly of said side wall to form a stop for one end of an expansion coiled spring 29 which is disposed in the bore 25. A headed pin 30 has its shank portion extending into the opposite end of the spring 29 and its head portion bearing against the said last mentioned spring end and against an edge of the lever 23 for urging the lever 23 to swing counterclockwise about its pivot 24, as seen in Figure 6. A stop pin 31 is secured in the tension body 17 and extends perpendicularly through the slot 22 and is engaged by the lever 23 to limit the swinging movement of the lever under the action of the spring 29.

40 The portion of the lever 23, which is disposed remote to its pivot 24, projects outwardly beyond the slot 22 and has a rod 32 fixed thereto and extending upwardly therefrom. The tension body 17 has a top portion 33 extending beyond its front wall 34 and which overlies the forward end of the lever 23 and the rod 32. The under surface 35 of said ledge portion 33 is provided with an arcuate groove 36 which re-

ceives the upper end of the rod 32 and in which said upper end is slidably guided when the lever 23 is swung on its pivot 24. A yarn guide pin 37 extends outwardly and downwardly from the front wall 34, remote to the position of the lever 23 when the latter is held against the pin 31 and abuts a part of the shuttle nose 14 to close the upper part of the cavity opening 16.

From the foregoing it will be readily apparent that all of the elements constituting the compensating spring take-up tension are demountably supported by the tension body 17 with only slight modifications thereof so that the tension body, with the attachment 21, may be readily mounted in a conventional manner in the depression 15, as illustrated in Figures 1 and 2, and secured therein by the fastening 18 which extends through an opening 38 of the tension body.

The yarn or filling 13 extends forwardly from the bobbin 12 longitudinally through the channel 19, between the yieldably gripping pads 20 and thence forwardly, as illustrated in Figure 1, around the upstanding rod 32 and then laterally beneath the ledge 33 and pin 37 and outwardly through the opening 16. Whereas the pads 20 of the conventional tension merely resists movement of the yarn through the tension from the bobbin 12, the attachment 21 additionally functions to take up slack in the portion of the yarn or filling 13 which has passed outwardly through the opening 16 and which is in no way accomplished by the conventional tension 17. When the shuttle 10 is operating in a conventional manner in a loom, not shown, the pull on the end of the yarn which extends from the opening 16 will exert a sufficient pressure against the rod 32 to cause the lever 23 to be swung clockwise on its pivot 24 to its position as shown in dotted lines in Figure 6 against or substantially against the inclined wall 39 of the slot 22 to thereby compress and load the spring 29. Consequently, when the shuttle 10 strikes the loom picker, not shown, slack will occur in the portion of the yarn which has passed outwardly through the opening 16 and the spring 29 will expand to swing the lever 23 back towards its full line position of Figure 6 to thereby take up this slack and tension the yarn to eliminate serious defects in the woven cloth, which would otherwise occur, such as rough cloth, and will likewise prevent kinking of the filling, loose picks and backlashes. The attachment 21 may be utilized with any type of yarn or filling to maintain a uniform tension at all times thereon and is especially adapted to modern high-speed looms.

It will also be apparent that the shuttle body 10 requires no modification for use of the attachment 21 with a conventional tension.

Various modifications and changes are contemplated and may obviously be resorted to, without departing from the spirit or scope of the invention as hereinafter defined by the appended claims.

I claim as my invention:

1. The combination with a loom shuttle tension having means for frictionally gripping the filling passing therethrough to resist the feed of the filling from a shuttle, of a compensating spring take-up tension for use with the shuttle tension, said shuttle tension including a body having a slot formed therein, said body being provided with a socket extending through a part of the body and having an end opening into said slot, a lever having one end disposed in said slot and an opposite end projecting outwardly from a front wall of the tension body, a pivot pin extending through the first mentioned lever end and anchored in the tension body for swingably mounting the lever in said slot, an expansion spring disposed in said socket and urging the lever to swing in one direction, said tension body having a ledge portion overlying and extending outwardly from its front wall and provided with an arcuate guide groove in its under surface, and a rod fixed to and rising from the last mentioned, outer end of said lever having an upper end slidably engaging said guide groove, said rod being adapted to have the yarn or filling engaging around its outer side for exerting a pressure on the lever to swing the lever in the slot and against the action of the spring for normally maintaining the spring in a loaded condition whereby the lever is swung under the biasing action of the spring when slack occurs in the yarn for tensioning the yarn.

2. A device as in claim 1, and a stop pin extending perpendicularly through the said slot and engaged by the lever when swung by the biasing action of the spring.

3. A device as in claim 1, and stop means disposed against a wall of the tension body and forming the opposite, closed end of the socket.

4. A device as in claim 3, said stop means comprising a plate and means for detachably fastening said plate to said last mentioned wall, said plate being removable for opening the last mentioned socket end to remove and apply the spring.

5. A device as in claim 1, and a headed pin having a shank portion disposed in the spring and a head portion disposed against one end of the spring and against a portion of said lever.

CHARLES H. DURHAM.
